P. J HARDY.
FOLDING CHAIR.

No. 33,082.

Patented Aug. 20, 1861.

UNITED STATES PATENT OFFICE.

PETER J. HARDY, OF NEW YORK, N. Y.

CAMP-CHAIR.

Specification of Letters Patent No. 33,082, dated August 20, 1861.

To all whom it may concern:

Be it known that I, PETER J. HARDY, of the city and State of New York, have invented, made, and applied to use a certain 5 new and useful Improvement in Folding or Camp Chairs; and I do hereby declare that the following is a full, clear, and exact description of my said invention, reference being had to the annexed drawing, making 10 part of this specification, wherein—

Figure 1, is a side elevation of my chair as folded for transportation. Fig. 2, is an elevation when extended as a chair. Fig. 3, is an elevation in a reclining position. Fig. 15 4, represents my chair as extended to form a camp bedstead and Fig. 5, is a plan of the framework on one side.

Similar marks of reference denote the same parts.

20 In the drawing *a a*, are side pieces and *b b*, cross pieces forming the seat of my chair; this as well as the back and foot support may be covered with cane work or any desired upholstery.

25 *c*, is the back framed and united to the seat by the joints 1.

d is a curved link attached to *a*, by the joint 2, and guided in the notched support 4.

30 *e*, is the arm of the chair attached to the back *c*, by the joint 5, and provided with a slotted end sitting over and taking the notches 3, 3, in the link *d*, so as to regulate the inclination of the back *c*, to the seat *a*, as illustrated in the various figures.

35 I provide a pair of legs *f* hinged at 6, to the rear part of the seat *a*, and connected to each other by the cross piece *g* near the center, and a second pair of legs *h*, are hinged at 7 to the front edge of the seat *a*,

40 and connected by the cross piece *i*. When these legs are placed in an X form the cross pieces *g* and *i*, coming in contact sustain the seat as seen in Figs. 2 and 3, but when the legs are folded closely together as seen in

45 Figs. 1 and 4, so as to set up against the under side of the seat *a*, the chair rests on the short feet 9, 9, projecting from the legs *f*, and in this position the cross bar *g*, occupies notches 8, in the legs *h*.

To form a support for the feet and legs 50 I provide the frame or foot board *k*, framed with cross pieces 10, 10, and attached to the seat *a*, by the cross rod of the joint 7 and *l*, is a pair of supporting legs attached at 11, to the foot support *k*. By these legs *l*, the 55 parts are sustained as in Fig. 3, or they may be folded under as seen in Fig. 4. When this support *k*, is not in use it folds away between the legs *h*, coinciding with them, see Figs. 1 and 2.

60 The whole article when not in use can be folded into a very small compass as seen in Fig. 1, and can be easily transported from place to place.

If desired the curved link *d* might have 65 notches cut thereon as at 12, (shown in red lines on the drawing) taking the support 4, on the back *c*, whereby the back *c*, will be retained in any desired position. If said notches 12 are used the arm *e*, might be dispensed with, or said arm may be used if preferred, but does not in any way tend to support the back *c*, because the notches 3, 3, are not used.

What I claim and desire to secure by Letters Patent is—

1. The combination of the curved notched link *d*, hinged to the seat, with the curved arm *e*, hinged to the back, in the manner and for the purposes specified.

2. The legs *f* with the cross piece, *g* in combination with the legs *h*, and cross piece, *i*, in the manner specified whereby the seat is sustained by the pieces *g* and *i*, coming in contact when the legs are in an X form as set 85 forth.

3. The supporting frame *k*, attached by the cross rod of the joint 7, and fitted to fold between the legs *h*, and beneath the seat when the chair is folded as specified.

In witness whereof I have hereunto set my signature this second day of July 1861.

P. J. HARDY.

Witnesses:

THOS. GEO. HAROLD,
I. P. KAYSER.
